BY Harry A. Beiner
ATTORNEY

UNITED STATES PATENT OFFICE.

ALEXANDER IZEN, OF ST. LOUIS, MISSOURI.

BED.

Application filed May 11, 1922. Serial No. 560,957.

To all whom it may concern:

Be it known that I, ALEXANDER IZEN, a former subject of the former Czar of Russia, who have declared my intention of becoming a citizen of the United States, residing at St. Louis, State of Missouri, have invented certain new and useful Improvements in Beds, of which the following is a specification.

10 My invention has relation to improvements in beds, and more particularly to those known in the trade as combined day-beds and couches, and it consists in the novel features of construction more fully set forth 15 in the specification and pointed out in the claims.

The object of the present invention is to provide a combined day-bed and couch that may be knocked down for packing so that it 20 can be shipped in a comparatively compact crate. Further objects are to provide a day-bed and couch having a sliding section and main section, both of which are supported by the head and foot pieces of the bed; one 25 that is rigid but compact; one in which the supporting rails for the sliding section are easily removed to permit assembling the main section with the head and foot pieces; and one possessing further and other advantages better apparent from a detailed description of the invention in connection with the accompanying drawings, in which—

Figure 1 represents a plan of my improved day-bed and couch with parts broken away 35 and the fabric removed; Fig. 2 is a combined front elevation and longitudinal section taken on the line 2—2 of Fig. 1; Fig. 3 is an end elevation of the bed; Fig. 4 is an enlarged side elevation of the main section 40 corner bracket mounted on the bed-post; Fig. 5 is an end elevation of the same; Fig. 6 is an enlarged side elevation of the sliding section corner; Fig. 7 is an end elevation of the same; Fig. 8 is an enlarged end elevation 45 of the outer end of the sliding section showing the hinged leg and brace therefor; Fig. 9 is a plan of the same with parts in section; and Fig. 10 is a detached view of the rail for supporting the inner end of the 50 sliding section.

Referring to the drawing, 1, 1 represent the two end pieces (head and foot) between which is supported the bed-bottom B which with ends constitute a three-piece bed, and 55 may be so used. In the present case the ends are bent from a single piece of tubing, and

the posts 3, 3 are spanned by a rod 4 securely fixed in each post. The bottom B consists of angle-iron ends 5, 5 and the angle-iron sides 6, 6 dropped below the ends, the ends 60 and sides being connected at each corner by a corner bracket 7 consisting of a vertically disposed angle, the legs a, b of which are turned outwardly, the former having the ends 5, 5 riveted to them at the top, and the latter having the sides 6, 6 riveted to them at the bottom. A diagonal brace 8 extends from the leg b of each bracket to the vertical leg of the side angles at each end. The legs b of the corner brackets 7 are each 70 provided with an open slot s having a vertical component s', and in assembling the end pieces 1, 1 and bottom B, the brackets 7 are brought into engagement with the legs 3, 3 by causing the rod 4 at each end to enter the 75 slots s and letting the bed-bottom B down until the rods 4 are received in the upper end of the vertical component s' of the slot s. The parts thus far described when provided with a fabric 9 stretched between the ends 80 5, 5 constitute a three-piece bed which is provided with a sliding section S (about to be described) for converting the same into a couch. The sliding section consists of angle-iron ends 10, 10, and angle-iron sides 85 11, 11' dropped below the plane of the ends, the ends and sides being connected at each inner corner by an inclined angle-iron bracket 12, the legs c, d of which are turned 90 inwardly, the former having the adjacent ends of the sides 11 riveted to them at the bottom, and the latter having the adjacent ends of the end angles 10 riveted to them at the top. A brace 13 extends from the 95 top of each leg c of the brackets 12 to the vertical leg of the side angles 11. The outer ends of the angles 10, 10 have vertical legs 14, 14 hinged to them at 15, and the side angle 11' is riveted at the ends to the legs 14, 14. Consequently, for collapsing the 100 sliding section S, the legs 14, 14 may be swung inwardly as one member on their hinges 15, 15, which yield inwardly, but will not permit the legs 14, 14 to move outwardly beyond a vertical position. When the legs 105 14, 14 are in a vertical position the upper edge m are in a vertical position the upper edge m of each engage the under side of the horizontal component of the end angles 10, 10, thus preventing further outward movement. In order to prevent the legs 14, 14 from being 110 accidentally displaced inwardly, I provide a corner latch 16 for each, one end 16' of the

latch being hinged to the horizontal component of the angle 10, while the other end 16" may be wedged into the corner *r* between leg 14 and side rail 11', the end 16" being 5 tapered slightly to more easily be forced into operative position.

In order to assemble the sliding section in cooperative relation with the main section, a supporting rail or channel 17 must first 10 be provided at each end for the inner side of the sliding section, the rail 17 being riveted to supporting arms 18, 18 which terminate in hooks 18', 18' at their free ends, said hooks being dropped over the rod 4 with the rail 15 17 turned inwardly so as to rest on the braces 8, 8. The rail is now substantially placed, since it is confined and held against sliding on the rod 4 by contact of the arms 18 with the brackets 7, 7, while the braces 20 8, 8 support it firmly.

It will be observed that an angle block 19 is riveted to the leg *d* of each bracket 12, and when the inner end of the sliding section *S* is positioned below the main section for 25 cooperation therewith, this block 19 will ride in the rail or channel 17, thus supporting the inner side of the sliding section.

The ends 17' of the channel 17 are closed, thus preventing the block 19 from being 30 pulled or pushed off the channel.

By turning the vertical legs of the end angles 5, 5 upwardly (Fig. 2) they provide abutments between which the mattress *M* is confined.

35 The legs 14, 14 of the sliding section are provided with rollers 20, 20 so the section will slide in and out more easily.

Having described my invention, I claim:

40 1. In a bed, the combination of a main section and sliding section, said main section having a head and a foot end, means on the head and the foot end for supporting the sliding section at one side, the sliding section having end rails and a side rail secured thereto at one side, the sliding section having 45 legs hinged to the end rails at the other

side, a side rail connecting said legs, and a latch for each leg pivotally connected to the end rail and adapted to be wedged between the leg and side rail secured thereto. 50

2. In a bed, the combination of a main section and a sliding section, said main section comprising a head and a foot end, and a bed-bottom detachably supported thereby, supporting rods extending from one post to the other of both head and foot ends, said bed-bottom having corner brackets supported by said rods, a rail carried by the rods, and means on the inner side of the sliding section for cooperatively engaging said rail 55 for supporting the sliding section. 60

3. In a bed, the combination of a main section and a sliding section, said main section comprising a head and a foot end, and a bed-bottom detachably supported thereby, the bed-bottom being provided with end rails and side rails, a corner bracket connecting said rails, and a brace extending from said bracket diagonally to the side rails, supporting rods extending from one post to the other of both head and foot ends, the corner brackets of the bed-bottom being supported by said rods, a rail bearing on said corner braces and having supporting arms in spaced relation, said arms terminating in 70 engaging means for the supporting rod, and means on the inner side of the sliding section for cooperatively engaging said rail for 75 supporting the sliding section.

4. A three-piece bed comprising a head 80 and a foot end and a bed-bottom, a rod extending from post to post of both head and foot ends, said bed-bottom comprising angle-iron end rails, side rails disposed below the end rails, and an angle-iron corner connecting the end rails and side rails, and each of said corners being provided with a slot 85 for engaging one of the rods adjacent each post.

In testimony whereof I hereunto affix my 90 signature.

ALEXANDER IZEN.
